INVENTOR:

John C. Lake,
By Myself.

ATTORNEYS.

UNITED STATES PATENT OFFICE.

JOHN C. LAKE, OF BIG PRAIRIE, OHIO.

REIN-HOLDER.

SPECIFICATION forming part of Letters Patent No. 233,521, dated October 19, 1880.

Application filed August 25, 1880. (No model.)

To all whom it may concern:

Be it known that I, JOHN C. LAKE, a citizen of the United States, residing at Big Prairie, in the county of Wayne and State of Ohio, 5 have invented certain new and useful Improvements in Rein-Holders; and I do hereby declare the following to be a full, clear, and exact description of the invention, such as will enable others skilled in the art to which it appertains 10 to make and use the same, reference being had to the accompanying drawings, and to letters or figures of reference marked thereon, which form a part of this specification.

My invention relates to an improvement in 15 rein-holders; and it consists in the holder-frame A, having the horizontal apertures a and b, for reception of the pivoted hook B, adjustable prong C of the rein-clasp D, the inclined recess d, spring-recess e, the concavity 20 f, for receiving the iron frame of the dash-board, the corrugated platform h, the corrugated rein-clasp D, dash-board clasp E, and in the combination and arrangement of the parts, as hereinafter more fully shown and de- 25 scribed.

In the drawings, Figure 1 is a top or plan view of my device. Fig. 2 is a detached view of the rein-clasp, showing the corrugations thereon. Fig. 3 is a horizontal sectional view. 30 Fig. 4 is a view of the under side thereof, the dash-board clasp being represented by dotted lines; and Fig. 5 is an elevation, showing the corrugated platform, the rein-clasp being removed.

35 A represents a suitable frame, having an aperture, a, for reception of the pivoted hook, which projects through it into the inclined recess d, and also having an aperture, b, for reception of the adjustable prong C, the hook

and prong being parts of the corrugated rein- 40 clasp D.

The frame is recessed at e for reception of the horizontal spring F, and it is corrugated at h to prevent the reins from slipping.

The method of inserting and holding the 45 reins is to first elevate, with the fingers placed in the ears a' a', the rein-clasp. The reins are then located between the corrugations of the frame A and rein-clasp D. The rein-clasp is elevated by overcoming the force of the spring 50 F, which binds it against the reins. The frame is also provided with the concave recess f, to fit the center piece of the dash-board.

The rein-clasp is pivoted at b', and the adjustable prong C is projected into the recess 55 e, which serves to hold it rigidly, that it may withstand any strain upon the reins.

E marks the dash-board clasp, which is secured to the dash and frame by the screws d' d', which are projected through the leather 60 and into the frame, thus rigidly securing the device to the dash-board.

The spring F, pressing upon the pivoted hook B, holds the rein-clasp firmly upon the reins, and the corrugations, provided respect- 65 ively in the rein-clasp and frame, serve to prevent the reins from being withdrawn from position.

What I claim is—

The frame A, having apertures a and b and 70 corrugations h, in combination with the rein-clasp D and spring F, substantially as shown, and for the purpose described.

In testimony whereof I affix my signature in presence of two witnesses.

Witnesses: JOHN C. LAKE.
